Primary Examiner — Susan Bennett Hattan*Assistant Examiner* — S. Bryan Reinholdt, Jr.(74) *Attorney, Agent, or Firm* — Weide & Miller, Ltd.(57) **CLAIM**

The ornamental design for a shooter's sandbag, as shown and described.

DESCRIPTION

FIG. 1 is a top view of a shooter's sandbag in a flat position, the bottom view being essentially the same as the top view, showing the new design;

FIG. 2 is a side view of a shooter's sandbag shown in FIG. 1, the left and right side views being essentially the same; FIG. 3 is front view of a shooter's sandbag shown in FIG. 1;

FIG. 4 is a rear view of a shooter's sandbag shown in FIG. 1;

FIG. 5 is a rear view of a shooter's in an alternately folded position, showing the new design; and,

FIG. 6 is a rear view of a shooter's sandbag in a rolled position, showing the new design.

The broken lines in FIG. 1 represent stitching and form no part of the claimed design.

1 Claim, 2 Drawing Sheets(56)
